ADA COLEMAN AND ISADORE A. COLEMAN, OF BALTIMORE, MARYLAND.

ADJUSTABLE BOOK COVER.

Application filed August 19, 1926. Serial No. 130,171.

This invention relates to improvements in adjustable book covers, and has for its object to provide a simple, cheap and efficient cover which can be readily adjusted 5 to any size book and secured in position thereon and which can also be readily removed when desired.

The invention consists of the novel construction of the parts and combination of 10 the parts hereinafter more fully set forth in the following specification and pointed out in detail in the appended claims.

In the accompanying drawings:

Figure 1 is a plan view showing the 15 leaves and one side of the book back in vertical position and the other side of back down and the cover folded over it and secured in position thereon.

Figure 2 is a plan view showing one side 20 of the cover folded over and the other side extended.

Figure 3 is a detail plan view of one of the folding tabs.

Figure 4 is a similar view to Figure 3 25 showing one of the tabs in the position it occupies when the cover is secured to the book.

Figure 5 is a detail section on a line 2—2 on Figure 4.

30 Referring to the accompanying drawing forming part of the specification and in which like reference numerals designate like parts throughout the several views thereof, 1 designates the sides of the cover which are provided with lines of indentation 2 on which the cover may be folded. Each of the sides 1 is provided with a number of fasteners 3 around which the cord 4 is wound and held to hold the cover in the 35 adjusted position on the book. On opposite ends of the cover is an approximately V-shaped tab 5 formed by cutting the cover inwardly on an incline. Each of these tabs 5 are folded back and held for part of their 40 distance by stitches 6 or in any other suitable manner, which permits the sides of the tabs when folded back in position shown in Figure 4, to extend over the edge of the portion out of which they are cut, thereby 45

50 preventing the tabs from being pulled out when folded under the book as well as preventing their edges from being exposed. These tabs 5 may be moved back and forth to accommodate size of book to which the 55 cover is to be secured. The tabs 5 project under the folded edge of the sides 1. The cover is held in position on the book by the cord 4 which is wound around the fasteners 3.

Having thus described our invention 60 what we claim is:

1. A sanitary, quick-detachable book cover comprising a blank having a side flap and top and bottom flaps, a friction disk secured at its center to each of said flaps, 65 the disks on the top and bottom flaps, when all the flaps are folded over the side and top and bottom edges of the book boards, being inset with respect to the disk on the side flap, so that the three disks define an 70 isosceles triangle, and a string, permanently fastened to the cover by means of one of the disks, frictionally engaging under the three disks in succession, whereby an inward pull is exerted on the side flap when the string 75 is tightly stretched between the disks, the string, throughout its length, when in securing position, resting on top of all three flaps.

2. A sanitary-quick-detachable book cover comprising a blank having a side flap and top and bottom flaps, externally projecting fastening means secured to each of said flaps, the fastening means on the top and bottom flaps, when all the flaps are 85 folded over the side and top and bottom edges of the book boards, being inset with respect to the said fastening means on the side flap, so that the three fastening members define a triangle, said fastening members being adapted to cooperate with a string which frictionally engages the same in succession, whereby an inward pull is 90 exerted on the side flap when the string is tightly stretched about the fastening members.

3. A sanitary, quick-detachable book cover comprising a blank having a side flap

and top and bottom flaps, a friction disk secured at its center to each of said flaps, the disks on the top and bottom flaps, when all the flaps are folded over the side and 5 top and bottom edges of the book boards, being inset with respect to the disk on the side flap, so that the three disks define a triangle, the said disks being adapted to be

frictionally engaged in succession by a string, whereby an inward pull is exerted 10 on the side flap when the string is tightly stretched between the disks.

In testimony whereof we affix our signatures.

ADA COLEMAN.

ISADORE A. COLEMAN.
